UNITED STATES PATENT OFFICE

148,993

DESIGN FOR A WATCH STANDARD

Reece W. Johnston and John C. Roberts,
Fort Worth, Tex.

Application December 8, 1947, Serial No. 143,024

Term of patent 14 years

(Cl. D42—10)

To all whom it may concern:

Be it known that we, Reece W. Johnston and John C. Roberts, both citizens of the United States and both residing at Fort Worth, in the county of Tarrant and State of Texas, have invented a new, original, and ornamental Design for a Watch Standard, of which the following is a specification, reference being had to the accompanying drawing, forming part thereof.

Figure 1 is an elevational view of a watch standard, showing our new design. Figures 2 and 3 are, respectively, side and plan views of the watch standard illustrated in Figure 1.

We claim:

The ornamental design for a watch standard, as shown.

REECE W. JOHNSTON.
JOHN C. ROBERTS.
